WEB TENSIOMETER

Richard L. Bowen, Jr., Pawtucket, R. I.

Application October 9, 1952, Serial No. 313,889

4 Claims. (Cl. 73—144)

This invention relates to tensiometers and more particularly to a device for determining the tension on a web of material.

One of the objects of the present invention is to provide a tensiometer reading of the tension on the web of cloth used in a coating machine.

Another object of the present invention is to provide a tensiometer reading of the tension on the web of cloth used in a coating machine and thereby permit the operator to manually adjust the controls of the machine to maintain a web tension in accordance with the tensiometer readings.

Other objects of the present invention will be pointed out in part and become apparent in part in the following specification and claims.

Uniform tension is a prerequisite to uniformity of product in many web processing machines such as textiles, paper, imitation leather, printing and the like. Especially is this true in coating machinery where the tension on the web effects the nature of the application of the coating being applied to the cloth. When a supply roll of cloth is placed in the machine the cloth is drawn off at a constant speed and at a given tension. As the diameter of the supply roll decreases, the speed or linear travel of the cloth is maintained constant. However, the tension on the cloth increases as the drag on the supply roll increases because the decreasing diameter produces more revolutions per minute. It is necessary to decrease the drag or friction on the supply roll shaft if the tension on the cloth is to be maintained constant. In the past constant tension devices have failed to give an instrument reading of the tension on the web. Past devices have also failed to automatically control the drag and regulate the tension accurately in accordance with a scientific indication of the tension. A tension curve of the present controls would be a straight line. The tension curves of present commercial controls would not be.

Referring to the drawings in which similar characters of reference indicate corresponding parts in all the figures:

Figure 1 is a schematic view of the essential elements of the new tensiometer.

Figure 2 is a perspective view of the nerve roller and the actuating mechanism.

Figure 3 is a detail view of the bellows in vertical cross section.

Figure 4 is a vertical sectional view of a diaphragm which is a substitute for the bellows.

Figure 5 is a schematic view of a recording pressure gage.

In proceeding with this invention there is provided a supply beam of web material 11 which is supported in the frame 12 of a plastic coating machine (illustrated by way of example). The web 13 passes over an idle roller 14 supported in frame 12. It then passes around a nerve roller 15 to a second idle roller 16 and on past a knife coating head to drying ovens and a windup roll. The last three devices are not shown because they are well known in the art.

The nerve roller 15 mounted upon a shaft 20 suitably

2

supported in the ears 21, 22 of a frame 23 which is pivotally mounted by means of shafts 26 and 26A in brackets 24, 25 secured to frames 12 and 12A.

A U-shaped arm 27 secured to the frame 12 has secured thereto a bellows 28 of the type commercially known as a Sylphon bellows. The bellows 28 responds to the position of frame 23 at 30. A pressure gage 31 of any conventional commercial manufacture is mounted in any convenient position on or off the frame 12. A tube 32 connects bellows 28 with pressure gage 31. A fluid contained in bellows 28, tube 32 and pressure gage 31 causes the latter to respond to the reaction of the former thereby indicating the position of frame 23 as it pivots on shafts 26 and 26A to indicate the position of nerve roll 15 in response to the tautness of web 13.

When a supply beam 11 is placed on frame 12 the web material 13 rolls off at a maximum diameter at a given number of feet per minute. As the beam diameter becomes smaller, the speed of supply beam 11 in R. P. M.'s increases thereby increasing the tension on the web. This increased tension affects the application of the coating material, producing a non-uniform coating and resulting in secondary product. By maintaining the tension constant or uniform, the coating application is more readily uniformly applied resulting in a high grade uniform product. To achieve this end a brake 35 mounted on frame 12 and acting on supply beam shaft 36 is manually controlled in accordance with the tension indicated on pressure gage 31.

Because tension control is so vitally important to first grade workmanship and hence quality product, it may be found expedient to substitute a recording pressure gage 39 in place of pressure gage 31. This would produce a permanent record of the tension applied to the individual supply beam of web material, thereby exercising production control. The recording pressure gage 39 is a commercially manufactured product.

Figure 4 depicts a diaphragm generally indicated by reference character 40 and comprises a two part housing 41, 42 fastened together by means of screws 43. Housing 41 is provided with a threaded shank 44 which may be secured to arm 27. A membrane 45 is positioned between the two parts of housing 41, 42 and is held in position by screws 43 intermediate chambers 46, 47 formed between the housings 41, 42. Tube 32 is secured in housing 41 and communicates with chamber 46. A plunger 48 slidably mounted in housing 42 and acting in chamber 47 upon membrane 45 is operatively connected at 30 to frame 23. As plunger 48 responds to the position of frame 23, membrane 45 will act upon the fluid in chamber 46 thereby causing the fluid in tube 32 to register on pressure gage 31 or recording pressure gage 39, as the case may be.

It becomes evident that a piston or other mechanical equivalent of a diaphragm 40 or a bellows 28 may be substituted for the diaphragm 40 and bellows 28 shown and described without departing from the spirit or scope of this invention.

What I claim is:

1. In a machine for maintaining uniform tension on a traveling web, a frame, a shaft provided with a brake drum rotatably mounted in said frame, a supply beam of web material fixed to said shaft, brake bands pivotally mounted in said frame engaging said brake drum, oppositely disposed idler rollers in spaced vertical alignment supported in said frame, a force responsive fluid pressure element supported in said frame, a pressure indicator fixed in said frame operatively connected to said force responsive fluid pressure element, oppositely disposed brackets in horizontal alignment secured to said frame, a second frame pivotally mounted intermediate said brackets, said second frame engageable and disengage-

able with said force responsive fluid pressure element, a nerve roller rotatably mounted in said second frame intermediate said idler rollers, said traveling web having a takeoff from said supply beam of web material to one of said idler rollers, thence to said nerve roller and to the other idler roller and beyond, said brake bands being manually operated in accordance with the reading on said indicator, said nerve roller reacting to the tension on said traveling web.

2. In a machine for maintaining uniform tension on a traveling web, a frame, a shaft provided with a brake drum rotatably mounted in said frame, a supply beam of web material fixed to said shaft, brake bands pivotally mounted in said frame engaging said brake drum, oppositely disposed idler rollers in spaced vertical alignment supported in said frame, a bellows fixed on one end to said frame, a pressure indicator fixed in said frame operatively connected to said bellows, oppositely disposed brackets in horizontal alignment secured to said frame, a second frame pivotally mounted intermediate said brackets, a nerve roller rotatably mounted in said second frame intermediate said idler roller, said second frame engaging and disengaging said bellows in response to the action of said nerve roller, said traveling web having a takeoff from said supply beam of web material to one of said idler rollers, thence to said nerve roller and to the other idler roller and beyond, said brake bands being manually operated in accordance with the reading on said indicator, said nerve roller reacting to the tension on said traveling web, said tension passing from said nerve roller to said second frame and thence to said bellows and said indicator.

3. In a machine for maintaining uniform tension on a traveling web, a frame, a shaft provided with a brake drum rotatably mounted in said frame, a supply beam of web material fixed to said shaft, brake bands pivotally mounted in said frame engaging said brake drum, oppositely disposed idler rollers in spaced vertical alignment supported in said frame, a diaphragm having a plunger, said diaphragm being fixed to said frame, a pressure recorder fixed in said frame operatively connected to said diaphragm, oppositely disposed brackets in horizontal alignment secured to said frame, a second frame pivotally

5

15 mounted intermediate said brackets, a nerve roller rotatably mounted in said second frame intermediate said idler rollers, said second frame engaging and disengaging said plunger in response to the action of said nerve roller, said traveling web having a takeoff from said supply beam of web material to one of said idler rollers, thence to said nerve roller and to the other idler roller and beyond, said brake bands being manually operated in accordance with the reading on said recording on said pressure recorder, said nerve roller reacting to the tension on said traveling web, said tension passing from said nerve roller to said second frame and thence to said plunger and through said diaphragm to said pressure recorder.

20 4. In a machine for indicating tension on a traveling web, a frame, a supply beam of web material supported in said frame, oppositely disposed idler rollers in spaced vertical alignment supported in said frame, a force responsive fluid pressure element supported in said frame, a pressure indicator fixed in said frame operatively connected to said force responsive fluid pressure element, oppositely disposed brackets in horizontal alignment secured to each side of said frame, a second frame pivotally mounted intermediate said brackets, said second frame being engageable and disengageable with said force responsive fluid pressure element, a nerve roller rotatably mounted in said second frame intermediate said idler rollers, said traveling web having a takeoff from said supply beam of web material to one of said idler rollers, thence to said nerve roller to the other idler roller and beyond, said nerve roller reacting to the tension on the web and indicating said tension on the pressure indicator.
